POST DRIVING APPARATUS

Alfred H. Nelson, Grove City, Minn.

Application May 13, 1949, Serial No. 92,971

2 Claims. (Cl. 254—29)

1

My invention relates to an improvement in post driving apparatus wherein it is desired to provide a means of driving posts through the use of the dump body of a truck or the like.

Various devices have been employed for driving fence posts and similar devices. Certain of these devices use the dump body of a truck or similar vehicle for producing the driving force. While such devices are probably capable of accomplishing their intended purpose, they are usually rather complicated in nature and costly to build. It is an object of the present invention to provide a fence driving apparatus embodied upon a truck having a dump body which is extremely simple and which may be applied or removed in an extremely short period of time.

The object of the present invention lies in the provision of a fence driving apparatus which includes a beam or other support which may be attached to the frame of a vehicle to extend transversely thereof and which may be applied or removed in an extremely short space of time. This beam, together with a bracket designed for attachment to the dump body incorporates all of the structure of my device. As a result a dump truck may be converted to a fence post driving device in an extremely short period of time.

A feature of the present invention lies in the simplicity of the structure. In the past it has been felt necessary to employ a vertical mast which carries the fence driving device. In the event the fence post should become slightly deflected due to engagement with a large rock or other object below the surface of the ground, a considerable strain is exerted on such previous structures due to the fact that they can travel only in a vertical line. In my construction a cap or similar device is provided for engagement with the top of the post and the cap is pulled downwardly by means of a suitable pulley arrangement. As a result if the fence post should strike an immovable object and should be deflected thereby, the angle of the post may be changed to some extent without injury to the driving mechanism or to the post. If the deflection of the post is excessive, the post may be removed and driven in another location.

A feature of the present invention lies in the fact that my device may be employed for either driving a post into the ground or pulling one from the ground. The member connected to the post is flexible and may be attached either to the upper end of the post or to the lower end thereof and the post may be moved in either direction.

2

A feature of the present invention lies in the fact that the member connected to the post is flexible. As a result the relative location of the driving and pulling mechanism need not be as precise as where the driving mechanism may move only in a single vertical line.

These and other objects and novel features of my invention will be more clearly and fully set forth in the following specification and claims.

In the drawings forming a part of my specification:

Figure 1 is a perspective view of a truck on which my post driving and pulling apparatus is mounted.

Figure 2 is a diagrammatic view of the front of the truck body showing the parts attached thereto.

Figure 3 is a perspective view of the bracket mounted upon the truck body for operating the driving or pulling cable.

Figure 4 is a perspective view of the operating end of the apparatus in position to pull the post from the ground.

Figure 5 is a perspective view of the cap for driving the post into the ground.

Figure 6 is a perspective view of a clamping device which may be used to pull the post from the ground.

The fence driving and pulling apparatus A is designed for use with a dump truck B. The dump truck B is preferably provided with a body 10 which is supported upon a transverse pivot so that the forward end 11 of the body 10 may be elevated. A suitable hoisting mechanism not illustrated in detail in the drawing is employed for elevating the forward end of the truck body. The truck B includes a chassis usually having a pair of laterally spaced frame members 12 and 13. The body 10 is supported spaced rearwardly from the cab 14 of the truck so as to expose a short length of the frame members 12 and 13 between the forward end 11 of the dump body and the rear of the cab 14.

A cross support or beam 15 is mounted upon the frame members 12 and 13 to extend at substantially right angles with respect thereto. This beam is mounted between the forward end 11 of the dump body and the rear of the cab 14 in position so that it does not interfere with the raising and lowering of the dump body. The beam 15 is held in place by U-bolts 16 or other suitable means. The U-bolts 16 extend over the beam 15 and connect the beam to the frame members 12 and 13.

A bracket 17 is preferably employed to con-

nect one end of the operating cable to the dump body 11. The bracket 17 is constructed as best illustrated in Figure 3 of the drawings and includes an inverted channel shaped body 19 including a top flange 20 and parallel side flanges 21 and 22. A horizontally extending flange 23 is connected to the lower end of the flange 21 to extend forwardly from the end 11 of the body 10. The distance the flange 23 extends is sufficient to space the cable away from the dump body so that it will not strike the body as the body is raised and lowered. A brace 24 may extend from a point near the top flange 20 to the extremity of the flange 23 so as to further support this flange 23.

An aperture 25 is provided in the flange 23 for accommodating the end of an eye bolt 26. The threaded aperture 27 may also be provided in the body flange 22 so as to accommodate a thumb screw or set screw by means of which the bracket may be secured in place on the body. The channel shaped portion 19 of the bracket is of proper size to accommodate the upper edge 29 of the body wall 11.

A pulley 30 is mounted upon the beam 15 below the bracket 17. The pulley 30 includes a rotatable pulley sheave 31 about which the operating cable 32 may extend. One end of the cable 32 is connected to the eye bolt 26, the cable end preferably being doubled through the eye of this bolt. The pulley 30 is preferably located so that the cable will extend directly down from the bracket 17 to the pulley sheave.

A double pulley 33 is supported at the outer extremity of the beam 15. This double pulley 33 includes a pair of spaced pulley sheaves 34 and 35 which are supported on parallel axes and spaced apart a distance just sufficient to accommodate the cable 32 therebetween. The cable 32 extends about the upper pulley sheave 34 when the device is being used to drive a post into the ground. The cable extends over the lower pulley 35 when the device is being used to pull a post from the ground.

A cap 36 is provided on the end of the cable opposite the end connected to the eye bolt 26. The cap 36 may be of various shapes and is shown as comprising a cylindrical body having an upper closed end 39. A pair of lugs 40 extend radially from the body 36 on opposite sides thereof and a pair of chain lengths 41 are flexibly connected to the lugs 40. The chain lengths 41 are connected together at 42 and connected to the extremity of the cable 32 in any suitable manner. The chain lengths 41 are of equal size and form a bridle by means of which the straight pull may be exerted upon the cap 36. A transversely extending bar 43 is secured in any suitable manner to the cab 14 of the truck. This bar 43 extends transversely in generally parallel relation to the beam 15. The bar 43 is connected by an off-set 44 to an arm end 45 which is located directly above the pulley 33. The off-set 44 is of sufficient length to compensate for the distance between the cab 14 and the forward end 11 of the truck body. A pulley 46 is mounted at the extremity of the arm end 45. A light cable or similar flexible connection 47 is secured to the closed end 39 of the cap 36 and extends over this pulley 46. A spring 49 is connected to the opposite extremity 50 of the bar 43 so as to exert an upward pull upon the cable 47. The spring 49 and cable 47 are of proper dimension to support the cap 36 above the level of a post before it is driven into the

ground. The spring 49 acts to return the cap 36 to elevated position after each post driving operation.

In the operation of my apparatus as a post driver, the post is placed alongside of the pulley 33 and in close proximity thereto and is held in vertical position. The cap 36 is positioned directly over the top of the post. The dump body 11 is then elevated in the usual manner so as to raise the forward end 11 thereof. This action causes a downward pull to be exerted through the cable 32 upon the cap 36, moving the cap over the upper end of the fence post 51 and moving the fence post downwardly. As the hoists raising the dump body are possessed of substantial strength, the post may usually be driven into the ground with little difficulty. The driving action may be stopped at any point by stopping the body elevating mechanism and allowing the body to drop into normal position. The spring 49 raises the cap 36 as the body 10 lowers.

In the event the fence post 51 strikes a rock or other obstruction and becomes deflected, the flexible connection between the cap 36 and the pulley 33 compensates for any angularity of the post. At the same time the cap tends to draw the post downwardly in vertical position unless the post is deflected by some solid mass. If the post becomes deflected due to such an obstruction the post may be driven at a slight angle or else may be withdrawn and driven in a slightly different location.

In Figure 6 of the drawings I disclose a device useful in removing the posts 51 from the ground. This device comprises a bracket having a pair of angularly extending flanges 52 and 53. The flange 53 is provided with a hook shaped projection 54 thereupon designed to accommodate the vertical flange of the post 51. The cable 32 is designed to extend through a suitable aperture 55 in the flange 52.

As the cable 32 is drawn upwardly the clamp produces a binding action upon the post which locks the member to the post and allows it to be pulled upwardly by the cable 32. In this event the cable 32 passes over the pulley sheave 35.

In accordance with the patent statutes, I have described the principles of construction and operation of my post driving and extracting apparatus, and while I have endeavored to set forth the best embodiments thereof, I desire to have it understood that obvious changes may be made within the scope of the following claims without departing from the spirit of my invention.

I claim:

1. A fence driving apparatus for use in conjunction with a truck having a dump body, the apparatus including a frame member extending laterally from the truck adjacent to the raisable end of the truck body, a bracket engageable with the upper edge of the body and including a forwardly extending portion, flexible means connected to the extending portion of said bracket and extending downwardly to said frame member, a pair of spaced pulleys on said frame member, one of said pulleys being at the outer end of the frame member, said flexible means operatively engaging with said pulleys, and means on the other end of said flexible means designed for engaging with the top of a post.

2. A fence driving apparatus for use in conjunction with a truck having a dump body, the

apparatus including a frame member extending laterally from the truck adjacent to the raisable end of the truck body, flexible means connected to the raisable end of the truck body and extending directly downwardly to said frame member, a pair of spaced pulleys on said member, one of said pulleys being at the outer end of the frame member, said flexible means operatively engaging said pulleys, an inverted cup member engageable with the top of a post, and 10 a bridle connected at opposite sides of said cup

member, said flexible means being connected centrally to said bridle.

ALFRED H. NELSON.
